CLAIM

We claim the ornamental design for a display screen or portion thereof with graphical user interface, as shown and described.

DESCRIPTION

FIG. 1 is a front view of a display screen or portion thereof with graphical user interface showing a first embodiment; FIG. 2 is a front view of the display screen or portion thereof with graphical user interface showing a second embodiment; FIG. 3 is a front view of the display screen or portion thereof with graphical user interface showing a third embodiment; FIG. 4 is a front view of the display screen or portion thereof with graphical user interface showing a fourth embodiment; FIG. 5 is a front view of the display screen or portion thereof with graphical user interface showing a fifth embodiment; and,

FIG. 6 is a front view of the display screen or portion thereof with graphical user interface showing a sixth embodiment. The broken lines in FIGS. 1-6 showing the display screen are for environmental purposes form no part of the claimed design. The broken lines in FIGS. 1-6 depicting text/words, numbers, symbols and other shapes in the graphical user interface currently form no part of the claimed design.
